MATERIAL DISTRIBUTOR AND SPREADER

Franklin E. Arndt, Galion, Ohio, assignor to The
Galion Iron Works & Manufacturing Company,
a corporation of Ohio

Application May 28, 1937, Serial No. 145,336

15 Claims. (Cl. 94—44)

This invention relates to road building machines adapted to distribute and level road material such as broken stone, gravel, or broken or finely divided materials on roadways, and is a continuation in part of each of my co-pending applications, Serial No. 556,340, filed August 11, 1931 for an Improvement in material distributors and spreaders, and Serial No. 679,019, filed July 5, 1933, for an Improvement in material distributors and spreaders.

One of the objects of the present invention is the provision of improved and efficient apparatus for hitching to a self-propelled dumping truck a road material spreader comprising a hopper having an open top and an open bottom and mounted on framework rendered self-supporting by road-engaging runners.

Another object of the invention is the provision of improved and efficient hitching apparatus for connecting to a towing vehicle a road material spreader having an offset open bottom for movement along a path at one side of the roadway and to firmly hold the forward upper edge of the spreader against the rear end of the frame of the towing vehicle to prevent swerving of the spreader while material is being discharged from said offset open bottom.

A further object of the invention is the provision of improved hitching mechanism for connecting at adjusted elevation a road material spreader to a hauling vehicle in such a manner as to maintain the spreader well balanced while operating along the roadway.

Another object of the invention is the provision of hitching mechanism for connecting to a towing vehicle a road material spreader, comprising draft elements connected to the spreader at various points to distribute the towing pulling strains thereon while maintaining the spreader in predetermined relation to the towing vehicle during operation.

A further object of the invention is the provision on the front side of a road material spreader of means for enabling draft elements to be connected to a towing vehicle and drawn taut for maintaining the spreader in predetermined relation to the towing vehicle during operation of the spreader.

Other objects of the invention will appear hereinafter, the novel features and combinations being set forth in the appended claims.

In the accompanying drawings,

Fig. 1 is a plan view of a road material distributing and spreading machine with hitching mechanism mounted on the front side thereof

and adapted to be connected to a towing vehicle;

Fig. 2 is a front view of the structure shown in Fig. 1, the dotted lines indicating the positions of the rear wheels of a towing vehicle relative to the spreader when the latter is connected to the towing vehicle;

Fig. 3 is a plan view of a portion of the spreader shown in Fig. 1, with modified hitching mechanism connected thereto;

Fig. 4 is an elevational view of one end of the apparatus shown in Fig. 1, showing in dotted lines the position of the self-propelled dumping truck for emptying road material into the spreader, and showing the spreader in coupling relation with the truck so that the front upper edge of the spreader will be held firmly against the rear end of the truck frame;

Fig. 5 is an elevational view of the right-hand end of Fig. 1, with the flexible draft chains removed;

Fig. 6 is a perspective view to illustrate another modification for connecting the towing chains or flexible draft elements to the front side of the hopper of a road material spreader;

Fig. 7 is a view similar to Fig. 4 to illustrate a modification of the mechanism for connecting the rear ends of the draft chains to the spreader at adjusted elevations; and

Fig. 8 is a view of that end of the spreader opposite to that shown in Fig. 7.

Referring more particularly to the drawings, a hopper 10 of metal plates and reinforcing angle irons is shown supported on framework comprising the supports 52, 52 and diagonal braces 35 53, 53. This framework in turn is normally carried on spaced-apart rollers 54, 54, arranged in two series of three each between two pairs of ground-engaging runners 55, 55, which are adapted to extend longitudinally of the roadway and 40 to project substantial distances forwardly and rearwardly of the hopper to render the hopper self-supporting on the roadway both when connected to a hauling vehicle and when disconnected therefrom.

The hopper 10 has a front wall 56 which is inclined downwardly and rearwardly. The rear wall 57 is inclined downwardly and forwardly. In the form shown in Fig. 1 the front and rear walls are symmetrical with each other. At one 50 end of the hopper 10, a vertical wall 58 extends longitudinally of the roadway between the walls 56 and 57.

Connecting the lower edges of the walls 56, 57, and 58 is a closed bottom wall 59, which inclines 55

downwardly from the vertical wall 58 to the edge 60 of the offset bottom opening 61 of the hopper 10 at that end thereof opposite the vertical wall 58, said edge 60 being located closely adjacent to the hard surface 62 of the roadway, as shown in Fig. 2. The lower portion 63 of the bottom wall 58 slopes at a greater angle than the upper portion 64.

As shown in Fig. 5, the front edge of the open bottom is located at 65, from which edge a plate 66 extends forwardly and downwardly. When material fills the hopper it may spread forwardly through the offset open bottom thereof under the edge 65 and the extension plate 66.

It should be particularly understood that the spreader comprising the hopper is adapted to be hauled by and behind a self-propelled dumping truck or other hauling vehicle to which the spreader is detachably connected. For this purpose the hitching mechanism shown in Figs. 1 to 5, inclusive, is provided, including a pair of chains 67, 67 the forward free ends of which are adapted to be connected to the frame of the truck, and the rear ends to an elongated draw-bar 91 connected to the front side of the spreader at adjusted elevation. Inasmuch as the spreader has an offset open bottom tending to swerve the hopper away from its operating position at right angles to the roadway, I will first describe the mechanism for controlling the spreading of the material from the open bottom so that this swerving tendency will be fully understood.

A road material spreader having an offset open bottom is particularly useful in connection with the widening of previously built or old roadways having hard surfaces, such as those having crushed stone foundations and finished on top with asphalt. At the edge of the hard-surfaced portion 62 of the roadway a trench 68 may be dug longitudinally and filled with crushed stone as shown in Fig. 2, by means of the spreader shown in Figs. 1 to 5, inclusive, 7 and 8; Fig. 6 illustrating a type of spreader for delivering material to a roadway entirely across the same.

The various forms of hitching mechanisms shown in the accompanying drawings are adapted to connect a road material spreader to a dumping truck by means of the hitching mechanisms shown, so that at all times the wheels of the truck and the wheels or runners of the spreader will remain on the hard surface of the previously built roadway. As shown by the dotted lines 69, 69 in Fig. 2, the wheels of the truck may occupy positions on the roadway 62 approximately the same as the paths of the wheels or rollers 54 and the runners or traction shoes 55. In other words, during operation of the spreader, the runners approximately track the wheels of the hauling vehicle.

While the crushed stone container or box 30 of the dumping truck is in the position shown in Fig. 4, and the rear gate 31 thereof is in open position, the truck wheels may be supported on the hard-surfaced roadway 62. Since the open bottom 61 in its laterally offset position will effect delivery of the material to the trench 68 which extends longitudinally of the roadway, as shown in Fig. 2, greater resistance will be encountered by the trench end of the spreader 70 than at the opposite end, and it is therefore desirable that the hitching mechanism will nevertheless hold the hopper in its operating position at right angles to the roadway.

In order to prevent crushed stone from rolling 75 onto the hard surface of the roadway, a for-

wardly extending guard or cut-off plate 72 is provided, as shown in Fig. 5 in full lines and in Fig. 1 in dotted lines. The lower edge 73 of the guard plate 72 is in longitudinal alinement with the inner edge 60 of the open bottom. Whatever stone 5 tends to roll under the hopper forwardly of the edge 60 of the discharge opening 61, will be deflected by the guard plate 72 into the trench 68 and consequently there will be no interference with the smooth travel of the spreader along the 10 roadway 62. That is to say, notwithstanding the elevation of the forward lower edge 65 of the open bottom, material discharged forwardly under such edge 65 will be prevented by the guard plate 72 from moving onto such hard surface and 15 therefore no discharged material will interfere with the front roller 54, located near the open bottom of the hopper.

The lower edge 70 of the end wall 58 constitutes the outer edge of the open bottom and is 20 elevated relative to the inner edge 60 of the open bottom, as shown in Fig. 2. Such outer edge 70 of the open bottom permits the stone to spread freely to the outermost limits of the trench 68 as shown at 71.

In order to regulate the depth of crushed stone laid down in the trench, a strike-off plate 74 is provided rearwardly of the open bottom. Wing end plates 75 are pivoted at 75' to the rearwardly extending vertical supporting plates 76 and 77 30 which are rigidly secured to the hopper 10.

Standards 78, 78 are mounted on the horizontal plate 79 which extends in a horizontal plane rearwardly from the rear edge 80 of the open bottom, which rear edge is at the lower end of that 35 portion of the wall 57 immediately above the open bottom. To the upper ends of the standards 78 is pivoted at 81 a tubular bearing 82 for the screw rod 83. Crank arms 84 are connected to the rod 83 to manually rotate the latter so as to advance or retract the screw rod 83 through the tubular nut 85. The latter is pivoted at 86 to the brackets 87 secured to the rear side of the strike-off plate 74. By turning the crank arms 84, the elevation of the strike-off plate 74 may be adjusted and consequently the crushed stone emerging from the open bottom of the hopper 40 may be stroked to secure the filling of the trench 68 to a predetermined depth.

By referring to Fig. 5 it will be seen that the 50 outer supporting plate 77 has its lower edge 70 located at a predetermined spaced distance above the horizontal plane extending through the surface on which the rollers 54 travel, while the inner supporting bracket plate 76 is extended down 55 into proximity to such surface so as to act as a guard plate to prevent crushed stone from spreading onto the hard surface of the roadway. In other words, by providing the plate 76 at the inner edge of the trench 68 approximately in 60 the plane of the cut-off plate 72, with the lower edge 88 in alinement with the inner edge 60 of the open bottom of the hopper, a vertical wall is formed for the inner end of the strike-off plate 74. Furthermore, the lower edge 73 of the forward guard plate 72 is also in alinement with the edge 60. The three lower edges 88, 60, and 73 co-operate to cut off both forwardly and rearwardly of the open bottom as well as under the same, the spreading of material onto the hard 65 70 surface of the roadway.

As an assurance that the wheels and runners will have free paths of travel, the forward wheels 54 of each series are enclosed in V-shaped guards 89, 89. From the foregoing it can readily be seen 75

that it is the action of the strike-off plate 74 which tends to swerve the spreader from its operating position at right angles to the roadway, and to resist this tendency the hitching mechanism hereinafter fully described, is particularly adapted.

When the pivoted box 30 of the dumping truck is in the position shown in dotted lines in Fig. 4, such stone enters the open top of the hopper and is received by the closed bottom 18 along which the material slides to the discharge opening 61, where it may spread outwardly under the edge 70 to fill a trench beyond, as shown at 71 in Fig. 2. The stone also spreads forwardly under the edge 65 and the plate 66 but is prevented by the cut-off plate 72 from spreading onto the hard surface 62 of the roadway where the stone might interfere with the rollers 54 or the runners 55 near the open bottom. The stone also spreads rearwardly under the plate 79 into the confined space bounded on the inner side by the guard plate 76, on the outer side by the plate 77 and at the rear by the strike-off plate 74. The lower edge 88 of the plate 76 is close to the hard surface of the roadway and therefore prevents spreading of the stone onto the latter.

The flaring of the interior of the hopper is preferably so proportioned with respect to the position of the runners 55, that the machine is always well balanced. That is to say, sufficient weight is maintained during operation, on the rollers shown at the right-hand end of Fig. 2, to keep the shallow end of the spreader at all times on the roadway. Tendency of the hopper 30 to tilt toward the trench is therefore obviated. The runners 55 are sufficiently elongated to extend substantially under the front and rear walls of the hopper to enable the rollers 54 to be positioned so as to maintain the hopper at all times in stable equilibrium against forward or rearward tilting.

It should also be noted that while Figs. 1 and 2 in the accompanying drawings show a right-hand trench filler, the latter may be left-handed, and in some cases such left-handed trench filler may be preferable since it enables the driver of the truck to better assist in moving the truck and trench filler more accurately along the road edge of the trench. It is preferred that the hitching mechanism shown in Fig. 1 should have the same arrangement relative to the open bottom as that shown in Fig. 1 when the spreader is a left-handed trench filler.

While mention has been made of crushed stone for filling a trench dug along the side of an old roadway, it should be understood that the structure shown is also adapted to receive and distribute various mixtures, such as stone dust or water and crushed stone, which mixture after being directed into the trench to a predetermined depth can be rolled into a compact trench filler and then covered with molten tar or asphalt, and again rolled flush with the surface of the previously built roadway and thereby provide the widening of the hard surfaced roadway. It will also be evident that brick, concrete or other previously built roads may be widened by spreading road building material onto the shoulders or into trenches dug along one side or the other or on both sides, and concrete poured from the truck into the mixer or hopper 10 while the latter is being hauled along the inner edge of the shoulder or the inner edge of the trench, with the open bottom 61 in the position shown in Fig. 2.

As the truck moves along while dragging the road material spreader by means of the hitching mechanism shown in Fig. 1, it is preferred that the upper front edge of the hopper be held tightly against the rear end of the frame 90 of the truck, as shown in Figs. 4 and 7. This may be done by means of the hitching mechanism shown in Figs. 1, 2, 4, and 5, or by means of the modification shown in Figs. 3, 6, 7, and 8.

In Figs. 1 and 2 an elongated drawbar 91, T-shaped in cross-section, extends along the front side of the spreader intermediate the top and bottom thereof and therefore substantially above the bottom and substantially below the top. To the rear side or vertical flanges of the T-shaped drawbar 91 are secured, preferably by welding, the spaced-apart clevises 92 which are adapted to be bolted through any one of a vertical series of perforations 93 to spaced-apart bracket plates 94 secured to the front side of the hopper 10, preferably by welding. The perforations 93 enable a vertical adjustment of the drawbar 91 to be made.

Secured to the ends of the drawbar 91 are bracket plates 95 each having a vertical notch 96 therein, as shown in Fig. 5, to receive a vertical link 97 as shown in Fig. 1, while preventing a horizontal link 98 from moving relatively to the drawbar.

The T-shaped drawbar 91 comprises a horizontal flange 99 having a plurality of series of holes 100, 100 extending therethrough. Bolted to the horizontal flange 99 by means of the perforations 100 are spaced-apart clevises 101, 101, each carrying a ring 102 through which one of the chains 67 may pass. The rings 102 may thus be positioned as desired along the drawbar 91, thus distributing the force of the pull of the truck between the clevises 101 and the end bracket plates 95. It should be particularly noted that the free ends of the chains 67 may first be connected to the truck and then passed through the rings 102 and drawn taut while the front outer edge of the hopper, as shown at 193 in Fig. 4, contacts the rear end of the truck frame 90. It will thus be seen that after the chains 67 are thus drawn taut, the available link 97 may be inserted in the notch 96 of the bracket plate 95 to effect firm holding of the upper forward edge of the hopper against the rear end of the truck frame. While the contact between the rear end of the truck frame and the upper forward edge of the hopper constitutes a fulcrum for limited tilting movement of the spreader when the runners travel over irregularities in the roadway, swerving of the hopper from its position at right angles to the roadway will be effectively prevented during operation of the strike-off plate 74 in its offset position at one side of the roadway. It should also be understood that the drawbar 91 may be connected at adjusted elevation to the bracket plates 94 so as to co-operate with the runners and such fulcrum to maintain a balanced relation between the towing pulls and the weight of the spreader and its load. The links 98 are at right angles to the links 97 and abut against the outside surfaces of the bracket plates 95 as shown in Fig. 1.

In the form shown in Figs. 7 and 8 the chains 70, 67' may be connected at their rear ends to clevises 22 held in position by bolts extending through selected holes in the inclined perforated plates 23 which are mounted on spaced-apart inclined braces 7 on the forward portion of the support 75.

ing framework below the front side of the hopper so that such perforations will be located substantially above the surface of the roadway and substantially below the open top of the hopper 10.

In the form shown in Fig. 3 a drawbar 91' is connected to the front side of the hopper 10 by means of the brackets 94, vertical perforated plates and clevises 92 in the same manner as illustrated in Fig. 4. The towing chains 67" are connected by means of the clevises 22', 22" as shown in Fig. 3, to selected holes 104, 104 in the horizontal flange 99' in the T-shaped drawbar 91'. The extra series of holes 105 at the right-hand end of the drawbar 91', as viewed in Fig. 3, may be used for the attachment of a third chain if desired. The form of hitching mechanism shown in Figs. 1, 2, 4, and 5 is preferred over the forms shown in Figs. 3, 7, and 8, not only because the strains exerted by the chains on the spreader are distributed in Figs. 1, 2, 4, and 5, but also because in the forms shown in these views the chains may first be connected to the truck and then drawn taut so as to hold the upper front edge of the hopper against the rear end of the frame of the truck before the links 97 are inserted in the notches 96 of the end bracket plates 95. In the forms shown in Figs. 3, 7, and 8 it is more difficult to connect the chains to the truck so that they will be taut for holding the upper forward edge 22 of the hopper against the rear end of the frame 90 of the truck during operation of the spreader while being towed by the truck.

As above explained it is highly desirable to secure the upper forward edge of the hopper tightly against the rear end of the truck frame so that the tendency of the hopper to sway or swerve laterally as it is pulled along the roadway, is overcome. Furthermore, the contact points between the forward upper edge of the hopper and the truck frame may serve as pivot points or fulcrums to permit limited tilting of the hopper as the road-engaging runners move over irregularities in the hard-surfaced roadway. I have therefore shown this feature of my invention in Fig. 6 applied to a spreader comprising a hopper having an open top and an open bottom for spreading material over a wide area transversely of the roadway rearwardly of the elongated road engaging runners 106, 106. An upright plate 107 is rigidly connected to the front side of the hopper intermediate the lateral ends thereof. Secured to the ends of this plate 107 intermediate the upper and lower edges thereof are two loops or rings 108, 108 for receiving the hauling chains in the manner illustrated in Fig. 1. Notched bracket plates 109, 109 are secured to the lateral ends of the front side of the hopper for receiving links of the hauling chains, the notched plates 109 corresponding to the notched plates 95 of Fig. 1. After the hauling chains are connected to the truck they may be passed through the loops 108 and after being drawn taut so as to hold the upper front edge 110 against the rear end of the frame of the truck, certain links of the chain may be inserted in the notches of the plates 109 so as to hold the said upper front edge 110 firmly against the rear end of the truck frame during operation of the spreader. By means of the double arm levers 111, 111 and mechanism connected thereto, the rear strike-off plate 112 extending between the lateral ends of the hopper may be adjusted in elevation.

For the purpose of connecting an additional

chain to the truck, a plate 113 may be connected at its ends to the runners 106, as shown in Fig. 6. At spaced-apart points on the plate 113 are mounted notched plates 114 and 115 so that the third chain may have a certain link thereof connected either to the notch in the plate 114 or to the notch in the plate 115.

In all of the forms of spreaders illustrated in the accompanying drawings the spaced-apart runners are sufficiently elongated and so connected to the framework supporting the hopper as to render the spreader self-supporting on the roadway and therefore most efficiently co-operate with the hitching mechanism to hold the hopper in such relation to the dumping truck as to prevent swerving of the spreader from its right angle position relative to the roadway. This is true even when the rollers shown in Figs. 1, 2, 4, and 5 travel on the hard surface of the roadway, because the rollers are distributed as shown in Fig. 1 so as to be located under the front and rear edges of the hopper as well as centrally thereof. When the surface of the roadway is relatively soft the rollers sink in and then the hopper is supported by both the rollers and the runners but mainly by the latter. The rollers, by reducing friction, materially reduce the power required to pull the machine along the roadway when acting to support the hopper. As above explained, forward and rearward tilting of the hopper relative to the supporting surface is prevented by the extension of the runners forwardly and rearwardly of the hopper sufficiently to produce stable equilibrium.

In the form shown in Fig. 5 a plate 116 may be connected by means of the bolts 117 and perforations 118 at adjusted elevation relative to the outer edge 70 of the lower bottom, thereby changing the effective outer edge of the lower bottom to the lower edge 119 of the plate 116. In the form shown in Figs. 7 and 8 such plate 116 of Fig. 5 is omitted.

In the form shown in Figs. 7 and 8 the spaced-apart runners 9 are not provided with any rollers and have extensions 33 at their forward ends, the lower surfaces of which are upwardly and forwardly inclined so as to facilitate movement of the spreader along the roadway and relieve the hauling chain 67' of undue strain. The hopper 10' is mounted on the runners 9 by means of the diagonal brace rods 7, 7, two of the forward ones of which may carry the perforated plates 23. Preferably the perforated plates 23 are welded to the forwardly and downwardly inclined brace rods 7 or if desired the perforations 55 may be located in these brace rods.

In Fig. 7 the forward downwardly inclined brace rod 7 is connected between the runner 9 and a plate 120 which may be welded to the bottom 13 of the hopper which bottom extends from the vertical wall 12 of the hopper downwardly to the offset open bottom. Near the offset open bottom the downwardly inclined brace rod 7 on which the perforated plate 23 is mounted, may be connected between the runner 9 and the metal strip 121 which is welded to the front side of the hopper.

In the rear wall 11 of the hopper is located a rear discharge opening of the open bottom between vertical rearward extending spaced-apart plates 39 and 39'. The lower edge of the outer plate 39 is in alignment with the outer lower edge 34 of the open bottom. The inner edge 60' of the open bottom is in alignment with the lower edge 88' of the plate 39'. Extending forwardly

from the lower front side of the hopper is a guard plate 32 the lower edge 73' of which is in alignment with the inner edge 60' of the open bottom.

5 The strike-off plate 36 as shown in Fig. 8 is provided with a reinforcing angle iron 40 extending along the lower edge thereof. Wing plates 37 connected to the ends of the strike-off plate 36 are pivoted at 76' to the spaced-apart vertical plates 39, 39'.

10 It should be understood that the outer vertical plate 39 is secured preferably by welding to the end wall plate 19 of the hopper, and that the plates 18 and 19 are in continuation of each other 15 above the outer lower edge 34 of the open bottom.

A horizontal plate 41 extends rearwardly from the rear wall 11 of the hopper and between the vertical plates 39 and 39'. Mounted on the plate 41 is a standard 42 which is secured intermediate 20 its ends by means of a plate 51 to the upper edge of the rear hopper wall 11. Pivoted at 43 at the upper end of the standard 42 is a swivel bearing 44 for the rod 45 which is screw-threaded at its lower end into the nut 47, the lower end of which 25 is pivoted at 48 to the bracket 49 secured to the upper portion of the strike-off plate 36. By turning the double arm lever 46 the elevation of the lower edge of the strike-off plate 36 may be adjusted. As above explained, the action of the 30 strike-off plate rearwardly of the offset open bottom tends to swerve the spreader from its right angle position relative to the roadway, but such tendency is resisted by the hitching mechanism which holds the upper forward edge 24 of the 35 hopper firmly against the rear end of the truck frame 90, as shown in Fig. 7.

In the form shown in Figs. 7 and 8 the hitching mechanism may be connected to the spreader at 40 adjusted elevation by means of the inclined perforated plates 23, and in the form shown in Figs. 4 and 5 the hitching mechanism may be connected to the spreader at adjusted elevation by means of the vertical series of perforations 93 at the forward end of the bracket plates 94. In the 45 form shown in Fig. 6 vertical series of perforations 123 are provided in the front vertical strips of the loop-shaped brackets 124, 124. The loops or rings 108, 108 may be provided with supporting plates 125, 125 each of which has a pair of 50 perforations so that such supporting plates 125 may be bolted to the brackets 124 by means of selected perforations 123.

Obviously those skilled in the art may make 55 various changes in the details and arrangement of parts without departing from the spirit and scope of the invention as defined by the claims hereto appended, and I therefore wish not to be restricted to the precise construction herein disclosed.

60 Having thus described and shown an embodiment of my invention, what I desire to secure by Letters Patent of the United States is:

1. Hitching mechanism for a road material spreader, comprising an elongated drawbar, a 65 plurality of draft elements, means for connecting said draft elements to said drawbar at spaced apart points thereon, and spaced-apart mechanisms connected to said drawbar at spaced-apart points thereon for connection to said draft elements intermediate the ends of the latter.

2. Hitching mechanism for a road material spreader, comprising an elongated drawbar, a pair of draft elements, means at the ends of said drawbar for connecting the end portions of said 70 draft elements to the ends of said drawbar, and

spaced-apart devices connected to said drawbar between the ends thereof and adapted to be connected to said draft elements so that the pulls on the drawbar by said draft elements will be distributed between the ends of the drawbar and the points where said devices are connected thereto.

3. Hitching mechanism for a road material spreader, comprising an elongated drawbar, means affording notches for the ends of said drawbar, draft chains each adapted to have a link extend into one of said notches, and spaced-apart devices connected to said drawbar between the ends thereof and adapted to be connected to said chains intermediate the ends of the latter so that the draft on said chains will be extended to the ends of the drawbar approximately longitudinally of the drawbar between said devices and the ends of the drawbar.

4. Hitching apparatus for connecting a road material spreader to a towing truck, comprising an elongated drawbar, a pair of flexible draft elements connected to the ends of said drawbar, and a pair of devices connected to said drawbar at spaced-apart points intermediate the ends thereof and having loops through which said draft elements extend freely to secure pulls longitudinally of the drawbar on those portions of the draft elements extending from the ends of the drawbar to said loops.

5. The combination of a spreader comprising a hopper having an open top and an offset open bottom mounted on a frame having elongated runners for rendering the frame and hopper self-supporting on a roadway, and haulage connections for connecting the spreader to a dumping truck in such position relative thereto as to maintain travel of the runners along the hard surface of the roadway with the said open bottom maintained in position to travel along one side of the roadway.

6. The combination with a spreader comprising a hopper with an open top and an offset open bottom supported on a frame having self-supporting road-engaging mechanism, of spaced-apart means for connecting a towing vehicle to said frame at adjusted elevations with the upper forward edge of the hopper in engagement with the rear end of the frame of such towing vehicle, and adjustable strike-off mechanism rearwardly of said open bottom, said spaced-apart connecting means serving to resist the tendency of said strike-off mechanism to swerve the adjacent end of the hopper away from the said vehicle frame.

7. Hitching mechanism for connecting a road material spreader to a towing vehicle, comprising an elongated drawbar, means adapted to connect such drawbar to the front side of the spreader, rings connected to said drawbar in spaced-apart relation and spaced from the ends of the drawbar, and notched plates secured to the ends of said drawbar and adapted to receive links of haulage chains extending through said rings.

8. Hitching mechanism for connecting a road material spreader to a hauling vehicle, comprising an elongated drawbar T-shaped in cross-section, a pair of draft elements adapted to be connected to such hauling vehicle, means for connecting the rear ends of said draft elements to the horizontal flange of said drawbar, and spaced-apart mechanism connected to the vertical flanges of said drawbar for connecting the latter at will to the front side of the spreader at adjusted elevation.

9. Hitching mechanism for connecting a road

75

- material spreader to a hauling vehicle, comprising an elongated drawbar T-shaped in cross-section and having a central flange, spaced-apart clevises secured to the back of said drawbar, 5 means comprising perforated plates for connecting said clevises to the front side of the spreader with the drawbar at adjusted elevation, and flexible draft devices for connecting the central flange of the drawbar to such towing vehicle.
10. 10. The combination with a road material spreader, of spaced-apart loops, means for connecting said loops at adjusted elevation to the front side of the spreader spaced inwardly from the lateral ends thereof, notched plates spaced laterally from said loops, and draft chains adapted to pass through said loops and have certain links inserted in the notches of said plates.
11. 11. The combination with a spreader comprising a hopper having an open top and an open bottom and framework for supporting the hopper with its open top and open bottom in predetermined positions relative to the surface along which the spreader is adapted to travel, and adjustable haulage connections adapted to extend horizontally to the said framework substantially above the bottom of the spreader so as to be adapted to be attached to a dumping truck to hold the forward edge of said open top in engagement against the rear end of the truck frame 20 to maintain delivery communication between the truck and said open top while said truck is hauling the spreader behind the same, and to secure the hopper against tendency to swerve as the spreader is moved along a roadway.
30. 30. The combination with a spreader comprising a hopper and framework for supporting the same, of spaced-apart perforated plates secured to the front side of said spreader in fixed relation thereto and substantially above the bottom thereof, an elongated drawbar adjustably connected at adjusted elevation to said perforated plates, and flexible draft elements adapted to connect said drawbar to a towing vehicle to hold the for- 35
- ward upper edge of the hopper in engagement with the rear end of the frame of the towing vehicle.
13. Hitching mechanism for connecting a road material spreader to a hauling vehicle, comprising an elongated drawbar, spaced-apart devices adapted to connect said drawbar to the front side of such spreader at adjusted elevation and substantially above the bottom thereof to extend transversely of the roadway when the spreader 10 is in operation, and spaced-apart clevises connected to said drawbar and adapted to be connected by means of draft elements to such hauling vehicle with the upper front edge of the spreader held against the rear end of the frame 15 of such vehicle substantially above said drawbar.
14. The combination with a road building spreader, of a pair of flexible draft elements adapted to be connected to a hauling vehicle, spaced-apart devices on the front side of the 20 spreader intermediate the ends thereof for receiving said flexible draft elements intermediate the ends of the latter, and additional devices spaced laterally from said first named devices and adapted to have end portions of said flexible draft 25 elements connected thereto to effect distribution of the pulls exerted by said flexible draft elements on the front side of said spreader.
15. Mechanism for connecting a road material spreader to a hauling vehicle, comprising the 30 combination with an elongated drawbar, of spaced-apart draft elements adapted to extend from the advancing side of the spreader to such hauling vehicle, spaced-apart devices intermediate the ends of said drawbar for connection to 35 said draft elements intermediate the ends of the latter, and additional devices on said drawbar spaced laterally from said first-named devices and adapted to have end portions of said draft elements connected thereto to effect distribution of the pulls exerted by the draft elements on said drawbar during operation of the spreader.

FRANKLIN E. ARNDT.
